UNITED STATES PATENT OFFICE

MATT J. HUCKLER, OF HOOD RIVER, OREGON

FIREPLACE SCREEN

Application filed March 5, 1929. Serial No. 344,417.

My invention is intended for use as a fireplace screen and consists primarily of two independent screen sections, with means being provided for raising and lowering each 5 of the screen sections independent of the other and for maintaining each of the sections in desired placed position; each of the screens may be manually manipulated to the full amount either up or down. Means are 10 further provided to independently raise each of the screens beyond their normal raising height.

The primary object of my new and improved device is to provide a screen that is 15 fixedly positioned relative to the fireplace front and providing means for the raising of each of the screen elements at a sufficient height to permit of the free laying and adjustment of the fire or to expose to full open 20 view, the fire when burning.

A further object of my new and improved device consists in providing means for the inspection and replenishing of the fire over the top of the screens when both of them are lowered to the full extent.

A further object of my new and improved device consists in providing a pair of screen elements each of which may be raised and lowered independently of the other and also 30 providing means whereby both may be manipulated simultaneously.

A further object of my invention resides in the construction and provides for the complete assembly at the point of manufacture 35 and which may be placed at the fireplace front and fixedly secured to the fireplace front if desired.

With these and incidental objects in view the invention consists in certain novel features of construction and combination of parts, the essential elements of which are set forth in the appended claims, and a preferred embodiment of which is hereinafter shown with reference to the drawings which accompany and form a part of this specification.

In the drawings:

Fig. 1 is the fireplace front, illustrating one of my new and improved screens in place with 50 the screens in closed position.

Fig. 2 is a sectional, plan view of the mechanism illustrated in Fig. 1, the same being taken on line 2—2 of Fig. 1, looking in the direction indicated.

Fig. 3 is a vertical, sectional view, taken on line 3—3 of Fig. 2, looking in the direction indicated.

Fig. 4 is a vertical, sectional view, illustrating the screens in normally raised position.

Fig. 5 is a front view of the device in position upon the fireplace front, illustrating the screens raised to their full height.

Fig. 6 is a front view of the device, illustrating both of the screen elements in full low position.

Fig. 7 is a perspective, sectional, end view of one of the frame structures.

Fig. 8 is a fragmentary, sectional, perspective view of one of the supporting columns 70 and illustrating the frame in position relative to the supporting column.

Fig. 9 is a fragmentary, sectional, plan view of one of the columns, illustrating the guideways disposed adjacent the inner edge 75 thereof into which the screened elements are adjustably positioned and illustrating the inner flange for fixedly positioning the column relative to the fireplace front.

Fig. 10 is a fragmentary, sectional, side view of one of the columns illustrating the telescopic relationship of the column section to facilitate raising the screens above their normally raised position.

Like reference characters refer to like parts 85 throughout the several views.

1 is the fireplace front. At oppositely disposed sides of the fireplace entrance, I place columns 2 and 3; each composed of an upper and lower portion, the upper portion being 90 telescopically disposed within the lower portion, each of the columns having an inwardly extending flange 4 adapted to engage the inner side walls 5 of the fireplace. The columns may be secured to the fireplace by any suitable 95 fastening means, as by threaded elements 6. Guideways 7 and 8 are disposed on the inner surface of the telescopic columns having a separating strip 9 extending longitudinally 100 of the inner face of the column to maintain

the screened element in spaced relationship with each other. The guideways are formed within the face of the upper and lower portions of the columns by the strip 9, the flange 10, and the inner extending side wall 11 of the column, thus forming two guideways 7 and 8 that are in spaced relation with each other into which the inner faces 12 and 13 of the respective screen element frames 14 and 15 extend; thus suitable guideways are formed for the raising and lowering of the screened elements.

I preferably form the frame for the screen of a structural metallic member, the top and bottom members of the frame being formed of angle bars 16 and 17; 18 and 19, and having connecting end strips 20 and 21 that connect the angle bars together to form a rigid structure and frame, into which suitable screens 22 and 23 are disposed. A locking strip 24 is disposed within the inner surface of the screen to secure the screen relative to the frame; suitable fastening holes 25 being disposed within the respective walls, through which threaded fastenings 26 pass for maintaining the screen in locked position relative to the frame. The lower frame has an inwardly extending foot 27 upon which the lower edge 28 of the upper screen contacts when each of the screens are raised to their normal full position. The upper surface of the upper screen has a supporting end 29 as illustrated in Fig. 8, adapted to engage and rest upon a supporting ledge 30 disposed within one of the walls of the guideway 11 of the telescopic column that maintains the upper screen in supporting position when inwardly pressed. When raised to full normal height the lower screen is supported by a locking catch 31 hingedly supported upon the supporting pin 32. When it is desired to exhibit the full fire to view without the screen interfering therewith, each of the screens are raised above their normal height, thus raising the upper end 33 of each of the telescopic columns sufficiently to engage the lower surface of the lower screen upon the supporting locking latch 33A; or, should it be desired to remove the screens entirely from their supporting telescopic columns, the upper end 33 of each of the upper portions of the columns is released from telescopic connection with the lower portion of the column in which position the screens and the frame may be removed from the frame at which time the upper portion of the column is placed back in telescopic relationship with the lower portion of the column. Hand engaging members 35 and 36 are secured to the respective frames to facilitate the manual manipulation and adjustment of the screens.

In order to increase the appearance of the device, I have found best results obtain wherein the frames for supporting the respective screens are formed with curved surfaces, with the curve extending outwardly,

as illustrated in Fig. 2, and at the same time giving greater utility to the screen by increasing the depth of the fireplace by the amount of the outwardly curved surface of the frame.

While the form of device herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a fireplace attachment, telescopic guideways securely disposed on each side of a fireplace, a screened frame slidably disposed within the lower sections of the guideways, a screened frame secured to the upper sections of the guideways, locking latches disposed in spaced relation on the lower sections of the guideways, and means disposed on the bottom lower ends of the frame slidably disposed within the lower sections for maintaining the upper frame when both frames are raised to their highest limits.

2. A fireplace attachment comprising guideways detachably attached to the sides of the fireplace, said guideways composed of upper and lower sections telescopically disposed, locking latches secured to the lower sections of the guideways, a frame slidably disposed within the lower section of the guideways, said frame having an inwardly extending foot disposed on each of its lower ends adapted to maintain the upper frame when both frames are raised to their highest limit, a frame secured to the upper sections of the guideways and screens removably attached to each of said frames.

MATT J. HUCKLER.
